UNITED STATES PATENT OFFICE.

EMERSON BELDEN, OF GREEN ISLAND, NEW YORK.

CORNER-BLOCK MACHINE.

SPECIFICATION forming part of Letters Patent No. 595,463, dated December 14, 1897.

Application filed January 16, 1893. Serial No. 458,472. (No model.)

To all whom it may concern:

Be it known that I, EMERSON BELDEN, a citizen of the United States, residing at Green Island, county of Albany, and State of New York, have invented certain new and useful Improvements in Corner-Block Machines, of which the following is a specification.

My invention relates to such improvements; and it consists of the novel construction and combination of parts hereinafter described and subsequently claimed.

Reference may be had to the accompanying drawings, and the letters of reference marked thereon, which form a part of this specification.

Similar letters refer to similar parts in the several figures therein.

Figure 1 of the drawings is a view, partly in side elevation and partly in central vertical longitudinal section, of my improved corner-block machine, the right-hand end being partly broken away. Fig. 2 is a vertical cross-section of same, taken on the broken line 2 2 in Fig. 1. Fig. 3 is a vertical cross-section of same, taken on the broken line 3 3 in Fig. 1. Fig. 4 is a longitudinal section of the adjustable yielding stop mechanism, taken on the broken line 4 4 in Fig. 2. Fig. 5 is a view in elevation of the right-hand end 30 of the stop mechanism as shown in Fig. 4. Fig. 6 is a view in front elevation of one of the adjustable block-supporting pieces detached from the carrier. Fig. 7 is a cross-section of the same, taken on the broken line 35 7 7 in Fig. 6. Fig. 8 is a plan view of a finished corner-block. Fig. 9 is a central longitudinal section of the yielding connection between the crank-pin and the toggle mechanism for operating the carrier. The last 40 six figures are drawn on an enlarged scale.

The object of my invention is to automatically feed and cut corner-blocks to form an ornamental rosette on each block; and my invention comprises a pair of rotary cutter-heads fixed upon opposite ends of a common shaft and mechanism for automatically presenting blocks one at a time to both cutter-heads simultaneously.

Referring to the drawings, A A' represent 50 a pair of rotary cutter-heads fixed upon opposite ends of the horizontal shaft A², supported in bearings A³ in the upper end of

the uprights A⁴ and connected by means of the pulley A⁵, fixed upon the shaft, and belt A⁶ with suitable driving mechanism (not shown) for imparting continuous rotary movements to the cutter-heads.

B B' are the block-carriers, one for each cutter-head, movable in the supporting-slideways B² B³ toward and from the heads, in axial line therewith, and provided each on its end adjacent to the cutters with a block-supporting head B⁴. The ways are each supported by the frame C of the machine, the way B² being formed integral with the bed-plate C' on one side and the way B³ being adjustably supported in the groove or channel C², formed in the other side of the bed-plate, as shown in Figs. 2 and 3.

The adjustment of the way B³ is accomplished by means of the screws C³, passing through the side wall of channel C² and bearing upon the outer edge of the adjustable way, whereby I am able to decrease the distance between the ways to compensate for 75 wear of the parts.

Reciprocating movements are imparted to the carrier by the flexion and expansion of the toggle-joint formed by the arms B⁵ B⁶, pivotally connected at their contiguous ends B⁷ and pivotally connected at their other ends, respectively, to a fixed support by the pivot B⁸, passing through the ears C⁴, depending from the bed-plate C', and to the carrier by the pivot B⁹, passing through the ears B¹⁰ on such carrier.

The toggle mechanism is operated by the crank-wheel D by means of the rod D', connecting the joint or knee B⁷ with the wrist-pin D² on the wheel. Power may be applied 90 to the crank-wheel shaft in any known manner.

When two cutter-heads fixed upon opposite ends of a common shaft and two carriers are employed, as shown, the two carriers are operated by duplicate toggle mechanism.

The toggle mechanism for operating the carrier shown at the right-hand end in Fig. 1 is shown in part only.

The movements of the duplicate mechanisms are made synchronous with each other by means of the connecting-rod D³, which is secured at its ends to the respective wrist or crank pins. Such an arrangement and move-

ment of the parts cause the blocks in the carriers to engage their respective cutter-heads simultaneously, and the end thrust imparted by one block to the shaft or spindle 5 which supports the cutter-heads is offset or balanced by the end thrust in the opposite direction imparted by the other block, thereby reducing the end friction and wear of the spindle upon its bearings to a minimum and 10 securing great uniformity in the product of the machine. The blocks may be placed in the carrier by hand or fed thereto automatically through the duplicate hoppers F F. The hoppers are provided with a carrier-way 15 leading from a platform F' to the vertical chute F². The bottom or floor of the way may be a movable carrier, as the belt F³, mounted upon the guide-rolls F⁴ F⁵ to carry the blocks F⁶ from the platform to the vertical chute. A friction-roll F⁷ projects through the vertical wall of the chute to engage the adjacent block and force it down the chute. The pulley F⁸, fixed upon the friction-roll shaft, is connected by belt F⁹ with the crank-shaft, as shown partly by dotted lines. The cogged wheel F¹⁰, fixed upon the friction-roll shaft, meshes with a similar cogged wheel F¹² 20 on the shaft of roll F⁴, and causes the friction-rolls and the floor of the carrier-ways to 25 move in the proper direction to feed the blocks. The mouth of the vertical chute is controlled by the body-plate B of the subjacent carrier. The blocks fall down the vertical chute and fill the same, the lower block 30 in the chute being supported by the block in the carrier when the carrier is in the position shown in Fig. 1.

When the carrier is advanced, the block in the carrier is pushed out from under the vertical column of blocks in the chute and the lower block therein rests upon the body-plate of the carrier. When the carrier returns empty to the position shown, the column of blocks descends until the lower block enters 45 the carrier, when the operation may be repeated.

The forward movement of the carrier is adjusted to force the blocks into engagement with the bits A⁷ of the cutter-heads to cut the 50 required depth therein.

The depth of the cut may be varied by varying the length of the arms of the toggle-joint or either of them. The piece a of one of the arms may be right and left hand threaded 55 at its ends and rotate in correspondingly-threaded sockets a'. By turning the piece a the arm can be either shortened or lengthened.

For the purpose of holding the block firmly 60 against the carrier-head while the cutter-bits are in engagement with the block and for pushing the block away from the bits in axial line with the cutter-head after the work of cutting is finished I provide a plurality of yielding stops, preferably one for each corner of the block, secured to the fixed bearings of the cutter-head spindle.

The stops H severally comprise a spindle

H', having an eccentric disk or head H², adapted to engage a corner of the block. The spindle is rotarily movable and movable end-wise in an inclosing barrel or support H³. A coil-spring H⁴, inclosed by the barrel, surrounds the spindle and bears at one end on a collar H⁵ on the spindle and at the other end on the bottom of the barrel. The screw-threaded plug H⁶ is centrally apertured to form a bearing for one end of the spindle and is inserted in the similarly-threaded open end of the barrel, the latter being centrally apertured at its bottom end to receive the other end of the spindle. The spindle projects through the bottom of the barrel and is provided with a fixed feather H⁸, adapted to fit a groove in the washer H⁹. The washer is centrally apertured to receive the projecting end of the spindle and provided with an enlarged opening to receive and fit the boss H¹⁰, projecting from the bottom of the barrel. The washer is also provided with a set-screw H¹², by which the washer can be fixed upon the boss. By revolving the washer upon the boss rotary movements can be communicated to the spindle and the eccentric head fixed to project at any desired angle from the spindle by means of the set-screw. The spindles are 95 fixed relatively to the axial line of the cutter-head and carrier and placed parallel to and equidistant from such axial line, and by rotatively adjusting them the several eccentric spindle heads or stops will be given a correspondingly radial adjustment relatively to the cutter-head and carrier. The object of such adjustment is to accommodate the stops to blocks varying in size.

The block is square and the round figure 105 cut therein covers most of its face, as seen in Fig. 8, the larger part of uncut surface being found at the corners. The stops are therefore arranged to engage the projecting corners, and since the blocks vary greatly in size 110 it is necessary to provide for radial adjustment.

The carrier-heads are provided with adjustable corner-pieces J, adapted to receive the lower corners of different-sized blocks and 115 support the blocks in the axial line of the carrier and cutter-head. Each of the block-supporting pieces has in its body part J² an elongated slot J³, adapted to receive an attaching-bolt J⁴. The head of the carrier is also provided 120 on each side with an open slot or recess J⁵, adapted to receive the attaching-bolt. The bolt, screw-threaded on one end, is inserted in the respective slots in the piece and head, as shown in Fig. 3, and secured to the head 125 by a nut J⁶. Vertical adjustment is secured by a vertical movement of the piece on the bolt and a lateral adjustment by a horizontal movement of the bolt in the recess J⁵. The pieces each have a flange or flanges projecting from the body part at right angles to the carrier-head.

The horizontal flanges J⁷ serve to support the block and the vertical flanges J⁸ to guide

the block by engagement with its vertical edges. The upper end J^9 of each vertical flange is made to flare outward to better guide the block onto the carrier as it falls from the 5 feed-chute.

By means of the vertical and horizontal or lateral adjustments of the corner-pieces I am able to support blocks varying considerably in size in axial line with the cutter-head.

10 To force the blocks down firmly upon the corner-pieces to give them a solid bearing, I provide the inclined presser-bar K , secured to the cross-bar K' , to be engaged by the upper edge of each block as it is borne by the 15 carrier to the cutter-head. The cross-bar is adjustably secured at its ends to the side rails of the main frame of the machine by bolts K^2 in slots K^3 , as shown in Figs. 1 and 2. The presser-bar is preferably a spring adapted to 20 yield slightly as the block engages it to compensate for accidental variation in the size of the blocks intended to be of uniform size.

After the blocks are cut and forced from the cutter-head by the spring-actuated stops 25 they are stripped from the carrier by means of the stripper S , which is a spring fixed upon the cross-bar S' and provided with an upwardly-inclined end S^2 , normally located in the path of the block, along which it is borne 30 by the carrier, as shown in Fig. 1. As the block passes over the stripper it forces down the end S^2 , which rises again to its normal position as soon as the block has passed. When the carrier returns, the block will strike 35 the end of the stripper and be forced from the carrier and fall to the floor beneath or into any suitable receptacle which may be placed to receive it. The upwardly-inclined end of the stripper will also serve as a guide 40 for the lower edge of the block as it falls from the feed-chute into the carrier.

In Fig. 3 and partly by dotted lines in Fig. 1 I have shown a modified form of stripper consisting of a finger S^3 , pivoted intermediate of its ends upon a cross-bar of the frame, the lower end of the finger being weighted to maintain by gravity the upper end of the finger normally in the path of the blocks. The 45 ends of the stripper-supporting cross-bars are screw-threaded and adjustably supported in the vertical slots S^4 by nuts S^5 . The strippers are adjusted vertically to correspond with the size of blocks to be cut.

I have ascertained that the blocks are given 55 a smoother finish and polish on the cut surfaces when the blocks are permitted to rest for a brief interval just as the cutter-bits have completed the cutting operation.

The cutter-head is preferably given five or 60 six thousand revolutions a minute, and the light contact of the moving bits with the cut surface of the blocks after the blocks are brought to rest gives the finishing polish. As a means for affording the blocks such rest interval I provide a yielding connection 65 between the driving mechanism and the reciprocating carrier and a stop for limiting the

reciprocating movements of the carrier in one direction before the completion of each successive periodical movement of the driving 70 mechanism whether such latter movement be rotary, reciprocatory, or vibratory. I have shown such yielding connection in the rod D' , connecting the crank or wrist pin with the toggle mechanism. This rod is shown in detail in Fig. 9 and is made up of the tube or barrel P , having a screw-threaded centrally-apertured plug P' inserted in one of the interiorly-screw-threaded ends of the barrel. The lower stem P^2 is pivoted upon the wrist-pin and is provided with a movable collar P^3 , adjustably fixed in position longitudinally of the rod by the adjusting-screw P^4 . The upper end of this stem is surrounded by the coil-spring P^5 and inserted in the barrel, as 85 shown. The other screw-threaded end of the barrel is provided with an inserted tube P^6 , exteriorly screw-threaded on one end and interiorly threaded on the other end. The exteriorly-threaded end is inserted in the barrel, and the other end receives the exteriorly-threaded end of the upper eyepiece P^7 . The lower end of the coil-spring bears upon the adjustable collar and the upper end upon the inserted end of tube P^6 . The resilient force 90 of the coil-spring is sufficient to maintain the connecting-rod D' at its full length until the toggle-arms have been forced into approximately the same straight line and the block-carrier to the desired limit of movement toward the cutter-head, in which position the toggle mechanism engages the stop P^8 on the bottom of the carrier-plate, as indicated by 95 dotted lines in Fig. 1.

The collar P^3 is so adjusted on the stem P^2 100 that the carrier has been forced to such limit of movement when the wrist-pin in its revolute movement around its shaft is several degrees back of that point which is in line with the axes of the crank-shaft and toggle-joint, so that the carrier will remain at rest while the pin is making the angular movement required to reach such axes-connecting line and an equal movement beyond such line, the coil-spring yielding sufficiently to 110 allow the lower stem P^2 to slide through the outer barrel into the tube P^6 . It is also desirable that the carrier should be given an interval of rest in the position shown in Fig. 1 115 to allow a block to be fed from the chute into the carrier. This is accomplished by the coil-spring P^9 , which is strong enough to force the carrier back against the stop P^{10} and hold it in that position while the wrist-pin passes through several degrees of angular movement 120 around the lower side of the crank-wheel.

What I claim as new, and desire to secure by Letters Patent, is—

1. In a corner-block machine, the combination with a rotary endwise-fixed cutter-head 130 and spindle, of a block-supporting carrier, carrier-supporting ways parallel with the axial line of the spindle and leading approximately to the head, reciprocatory mechanism

and means for reciprocating the same, a yielding connection between such reciprocating mechanism and the carrier, and stops for limiting the movements of the carrier,
5 whereby intermittent reciprocating movements may be imparted to the carrier, substantially as described.

2. In a corner-block machine, having a rotary cutter-head and a block-carrier movable
10 in axial line with the head to and from the head, a plurality of yielding steady and push

stops located in the path of a carried block, and adjustable radially to the axial line of the cutter-head and carrier, substantially as described.

In testimony whereof I have hereunto set my hand this 7th day of January, 1893.

EMERSON BELDEN.
